MERCURY INERTIA SWITCH

Reuben Erich, Avenal, Calif., assignor of one-third to William J. Erich and one-third to Walter G. Erich

Application April 18, 1934, Serial No. 721,146

1 Claim. (Cl. 200—52)

This invention relates to inertia switches, and particularly to one especially designed for use on a motor vehicle, to give direction signals by reason of changes of speed of the vehicle, and represents improvements in construction over the switch shown in my copending application for patent, Serial No. 668,529, filed April 29, 1933.

The switch as previously constructed was open to the objection that it was too easily affected by gravity as the horizontal level of the switch became changed when the vehicle on which it was mounted ascended or descended a grade.

The principal object of the present invention therefore is to eliminate this objectionable feature by constructing the switch so that gravity effect or action thereon is minimized, it can be arranged so that it may assume a greater critical angle than the previous type before being affected by gravity, while at the same time the signal giving action under all conditions is positive and as sensitive as with the previous type. The switch as now constructed also has the inherent feature of absorbing road shocks so that signals will not be unduly given when the vehicle is traversing rough roads.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claim.

In the drawing similar characters of reference indicate corresponding parts in the several views:

Figure 1 is a side elevation of the switch in a normal horizontal and inert position.

Figure 2 is a top plan view of the same.

Figure 3 is a sectional elevation of the switch when set on a slope approaching the predetermined critical angle.

Referring now more particularly to the characters of reference on the drawing, the switch comprises a tube preferably of glass and of what may be termed a compound U-L or Y-L shape. In other words the horizontal portion of the switch 2 is substantially of U-shaped form and comprises a pair of slightly diverging tube legs 1 both disposed in the same horizontal plane and connected at one end by a neck 2. A tube leg 3 of the same diameter as the legs 1 projects upwardly at a forward angle from the front of the neck centrally thereof so that said leg 3 includes an obtuse angle with the plane of the legs 1. In side elevation therefore the tube is substantially L-

shaped in form, while in plane it is Y-shaped in form, as clearly apparent from Figures 1 and 2 respectively. The tube as a whole is designed throughout with easy curves so as to reduce the resistance to mercury movement.

Toward the top the leg 3 is formed with a forwardly projecting substantially horizontal ledge 4; an electrode 5 projecting into the leg from in front and below the ledge so as to terminate above the latter adjacent its forward end. Another electrode 6 projects downwardly into the top of the leg 3 to a termination some distance above that of the electrode 5. A third electrode 7 projects into the tube neck 2 from the bottom.

Mercury 8 is in an amount sufficient to fill both legs 1 and to extend upwardly into the leg 3 to a termination slightly above the level of the ledge 4 is sealed in vacuum in the tube. The angle A included between the horizontal legs 1 and a line L drawn through the top of the mercury at both ends determining the critical angle at which the legs 1 may be set before the mercury will be acted on by gravity to cause said mercury to rise in the leg 3. This angle is preferably chosen, and the switch designed accordingly, to correspond to a degree of grade closely approaching what is ordinarily considered a dangerous grade.

When installing the switch in a motor vehicle, the legs 1 are of course disposed horizontal or parallel to the ground and if the switch is set so that the leg 3 is at the forward end, the switch serves for slow and stop signals particularly, as indicated in Figure 1. In such an installation the electrode 5 is connected to the "slow" signal lights 9, the electrode 6 is connected to the stop light 10, while the electrode 7 is connected to a source of current. Signals may also be given upon reversing the car and if two switches are used set in reversed relation to each other, the following combination of signals can be given:

1. Stop.
2. Slow down (forward moving direction).
3. Beginning a reverse movement.
4. End of reverse movement.
5. Beginning of forward movement.
6. Increase of speed in a forward direction.
7. Slow down in a reverse direction.
8. Beginning of left or right hand turns.
9. To indicate dangerous up or down grades.

My improved switch is constructed to operate by the displacement of mercury and on the well known law of physics that the mercury displaced in the leg 3 will equal the amount displaced from both horizontal legs 1, which amount is of course

double that displaced from either horizontal leg individually. In other words, the mercury displaced from both horizontal legs will be combined in the leg 3 and the latter being the same diameter as the legs 1, the extent of rise of mercury in the leg 3 will accordingly be twice the length of displacement of the mercury in each individual leg 1.

By reason of the position of the electrode 5 relative to the ledge 4 and the position of the level 10 of the mercury relative to the latter, contact of said electrode with the mercury is had with very slight displacement of the mercury in the legs 1, so that the action is very sensitive as is desirable for the particular signal connected to this electrode. It will therefore be seen that what I term 15 a multi-lift switch tube, which as far as I am aware employs a novel method of amplifying mercury displacement, overcomes the difficult problem of relative gravity directional changes on 20 varying grades. The principle of operation also, as previously stated, enables a relatively great critical angle to be used without interfering with the proper operation of the switch and also permits the electrodes to be spaced sufficiently far 25 apart to avoid possible confusion in signal giving while at the same time having the necessary positive and sensitive action.

The greater lifting potential or effect had in a tube of this construction allows the greater tangential component lifting force in rounding curves, so that the switch will close a sectional surface the instant a curve or side sway of any predetermined degree is encountered. Also this tube has the inherent feature of absorbing road 35 shocks.

While I have here shown and described and preferably used a switch tube having two horizontal legs, it will be obvious that the same principle may be employed with the use of three or more legs, which would enable an even greater 5 spacing between the electrodes in the upstanding leg while maintaining the sensitiveness of operation.

From the foregoing description it will be readily seen that I have produced such a device as substantially fulfills the objects of the invention as set forth herein.

While this specification sets forth in detail the present and preferred construction of the device, still in practice such deviations from such detail 15 may be resorted to as do not form a departure from the spirit of the invention, as defined by the appended claim.

Having thus described my invention what I claim as new and useful and desire to secure by 20 Letters Patent is:

A mercury inertia switch comprising a horizontal tube portion, an upstanding tube leg communicating with said horizontal portion at one end thereof, mercury normally filling said portion and 25 extending into the upstanding leg a predetermined distance, a substantially horizontal ledge formed on the interior of the upstanding leg adjacent the level of the top of the mercury therein and extending lengthwise of and away from the 30 horizontal tube portion, and an electrode projecting into said upstanding leg and terminating adjacent the outer end of said ledge.

REUBEN ERICH. 35
